UNITED STATES PATENT OFFICE.

RUDOLF WIETZEL AND FRANZ KREMP, OF LUDWIGSHAFEN-ON-THE-RHINE, GERMANY, ASSIGNORS TO I. G. FARBENINDUSTRIE AKTIENGESELLSCHAFT, OF FRANKFORT-ON-THE-MAIN, GERMANY, A CORPORATION OF GERMANY.

PRODUCTION OF FORMATES.

No Drawing. Application filed April 27, 1928, Serial No. 273,425, and in Germany May 28, 1927.

This invention relates to an improved process for the production of formates.

It is already known that alkyl formates are formed by the action of carbon monoxid, under pressure, on aliphatic alcohols in the presence of alcoholates.

We have now found that formates of the cyclic series are obtained when acting with carbon monoxid, or gases containing the same, on alcohols of cyclic compounds, preferably under a pressure higher than atmospheric, at elevated temperature and in the presence of alcoholates. The known working methods for the production of the alkyl formates are directly applicable to the above process.

The following examples further illustrate the nature of the invention, which however is not restricted thereto.

Example 1.

An autoclave is charged with cyclohexanol containing 1 per cent of metallic sodium in solution; and is heated to 90° centigrade. Carbon monoxid is then forced in under a pressure of 200 atmospheres, this pressure being maintained by the periodical or continuous admission of further carbon monoxid. The transformation will be complete at the end of four hours. After cooling down, and releasing the pressure in the autoclave, the product, consisting of 80 per cent of formate, is sucked off from the solid alcoholate, shaken up with a little water, separated from the latter, dried and rectified.

Example 2.

Benzyl alcohol with addition of 0.5 per cent of potassium, is treated at 80° centigrade with a gaseous mixture containing 60 per cent of carbon monoxid, and 40 per cent of nitrogen and hydrogen, a pressure of 200 atmospheres being employed. A good yield of the formate of benzyl alcohol is obtained.

What we claim is:

1. A process for the production of formates of the cyclic series which comprises acting on alcohols of cyclic compounds with carbon monoxid at an elevated temperature and in the presence of alcoholates.

2. A process for the production of formates of the cyclic series which comprises acting on alcohols of cyclic compounds with carbon monoxid at an elevated temperature in the presence of alcoholates and at a pressure higher than atmospheric.

3. A process for the production of cyclohexanol formate which comprises acting on cyclohexanol with carbon monoxid at an elevated temperature and in the presence of alcoholates at a pressure higher than atmospheric.

4. A process for the production of cyclohexanol formate which comprises acting on cyclohexanol with carbon monoxid at 90° centigrade and under a pressure of 200 atmospheres in the presence of sodium alcoholate.

In testimony whereof we have hereunto set our hands.

RUDOLF WIETZEL.
FRANZ KREMP.
